DRUM BEARING SHIELD

Bernard L. Michaelson, Sioux City, Iowa

Application August 9, 1956, Serial No. 603,143

1 Claim. (Cl. 77—55)

My invention relates to a drum bearing shield.

An object of my invention is to provide a shield in which a brake drum can be securely held on a suitable lathe when truing the inner surface of the drum, and wherein the iron cuttings from the tool will not be able to pass into the bearings.

A further object of my invention is to provide an arrangement of this type in which adjustable means are provided for accommodating the device to different sizes of attaching members.

A further object of my invention is to provide an arrangement in which the spring pressure applied is applied uniformly and smoothly around the shield.

With these and other objects in view, my invention consists in the construction, arrangement, and combination of the various parts of my device, whereby the objects contemplated are attained, as hereinafter more fully set forth, pointed out in my claim, and illustrated in the accompanying drawings, in which:

Figure 1 is a longitudinal section of my shield as applied to a brake drum.

Figure 2 is a sectional view of Figure 3 taken along the lines 2—2 thereof.

Figure 3 is a sectional view of Figure 2 taken along the lines 3—3 thereof.

My invention contemplates the provision of a brake drum shield which will efficiently seal the bearing portions of the drum from cuttings resulting from truing of the inner surface of the drum, and further contemplates adjustable means wherein different sized fittings can be accommodated. I have indicated certain standard portions by dotted lines in order to clarify the details of my invention, and as such I have used the character 10 to indicate the cylindrical portion of a brake drum of an automobile, the character 11 indicating the inner surface which is to be trued with a cutting tool.

I have further used the character 12 to indicate the fabric or other covering member of a lathe which terminates in the annular member 13, the character 14 indicating a spacer, the character 15 a cone, the character 16 an arbor, the character 17 a further cone, the character 18 a spacer, and the character 19 a tightening nut which is engaged with the threads 20 at the end of the arbor, the cones 15 and 17 being engaged with the hub portions 21 and 22 of the drum, this arrangement thereby serving to securely hold the drum so that it will rotate with the lathe portions for the cutting operation.

The character 23 indicates the usual reduced width annular surface which extends from the recessed portion 24, the inside of the hub portion including the usual ball bearings or other bearings which are to be protected.

The device of my invention comprises an outer cylindrical member 25 which is secured at 26 to a ring shaped member 27 having a central opening 28, and secured to the member 27 is the ring shaped resilient member 29, and I have further used the character 30 to indicate a further ring shaped member having the larger opening 31,

2

and attached to the member 30 is the further ring shaped resilient member 32. The member 30 received within the end of the cylindrical member 25 and can be removed therefrom.

Attached as at 33 to the ring shaped member 27 are the lengthened bolts 34 of which there are preferably three, equally spaced as shown, and receiving the bolts 34 are the helical springs 35 which normally bear at 36 against a further ring shaped member 37 having the central opening 38, the ring shaped member 37 having small opening 39 for allowing free passage of the bolts 34, and threadably attached at the ends of the bolts 34 are the nuts 40.

In using my device, the end portion 13 of the lathe is pressed firmly against the disk 37 which disk will compress the springs 35 a certain amount, which in turn will cause the resilient member 32 to tightly bear against the annular portion 23, so that when the entire brake drum turns, and as the tool cuts into the surface 11, it will be impossible for the cuttings to get into the bearings within the hub portion 22, etc. The various other members such as the cones 15 and 17 are assembled as explained above.

In many cases when a larger arbor is used, or when larger securing cones 15 are used, the outer member 30 can be pulled out of the cylindrical member 26, and the inner member 28 will be used with the resilient ring 29 being pressed against the annular surface 23, this arrangement thereby providing an adjustable feature for varying sizes of attaching means such as cones or other devices, it being further noted that these different sized end rings will also accommodate varying hub sizes without the necessity of using a separate shield.

The equally spaced springs 35 provide means for maintaining a uniform pressure against the hub surface, and in a simple construction. The length of the bolts 34 permit the unit to be used at a variety of desired spacings between the portion 13 and the hub portion 23 with sufficient compression in the springs to provide a tight joint where required, and it will now be noted that I have provided the advantages mentioned in the objects of my invention with further advantages being apparent.

Some changes may be made in the construction and arrangement of the parts of my invention without departing from the real spirit and purpose of my invention, and it is my intention to cover by my claim any modified forms of structure or use of mechanical equivalents which may be reasonably included within their scope.

I claim as my invention:

A drum bearing shield for turning lathes comprising an annular end ring having a resilient facing for bearing against a drum hub end, a further ring abutting against said end ring, said end ring and said further ring having different sized central openings for accommodating different sized fittings, a still further ring spaced from said end ring and said further ring, a cylindrical guard receiving all of said rings, peripherally and equally spaced bolts attached to said further end ring, said bolts passing through said still further ring, helical springs receiving said bolts and bearing against said further ring and said still further ring, nuts attached to the inner terminals of said bolts for limiting movement of said still further ring, said end ring and said further ring being secured to said cylindrical shield, said still further ring having a central opening in longitudinal alignment with said different sized openings.
